UNITED STATES PATENT OFFICE.

WILLIAM H. KESSLER, OF MERWIN, MISSOURI, ASSIGNOR OF ONE-EIGHTH TO JOHN T. HILTON,
OF MERWIN, MISSOURI.

FENCE AND HITCHING POST.

No. 904,487.

Specification of Letters Patent.

Patented Nov. 17, 1908.

Application filed January 25, 1906. Serial No. 297,852.

To all whom it may concern:

Be it known that I, WILLIAM H. KESSLER, a citizen of the United States, residing at Merwin, in the county of Bates, State of Missouri, have invented certain new and useful Improvements in Fence and Hitching Posts; and I do hereby declare the following to be a full, clear, and exact description of the invention, such as will enable others skilled in the art to which it appertains to make and use the same.

This invention has relation to posts for fencing, hitching and other uses.

It is the object of the invention to provide improvements in cement posts, as will enhance their durability, the scope of their usefulness, reduce in the end their cost and form a secure base for anchoring them in the ground, so that they will maintain their perpendicularity.

The essential feature of the invention comprises a concrete post having fixed in its longitudinal center a hollow rod extending from the top through the entire post, including the anchoring base, to its bottom in the ground. Connected to the rod at short intervals are cross-wires extending laterally as a binder to the concrete. The post is provided with holes running laterally through it for the stringing of wires therein, or for attaching to the post means for connecting and supporting the wires. The anchoring base is formed integral with the post body proper, and is provided with a facing or sheath of metal, the outer surfaces of the base and sheath being screw-threaded to give the structure good anchorage or hold in the ground.

It is well known that, perhaps next to wood, concrete or cement is the best material out of which to form posts for fences and other structures. Its durability is a feature of much importance, as is also the readiness with which it may be made into symmetrical form. Its drawbacks are concerned with the difficulties of giving it satisfactory anchorage in the ground and of providing its body portion with means so that wires and other devices may be connected therewith just as wanted. By the improvements I have made I materially advance its existing desirability and add some new qualities of importance and value thereto.

The drawings hereto annexed form a part

of this specification and reference is to be had thereto for an entirely clear understanding of the invention.

Of the said drawings, Figure 1 is a side elevation of the post. Fig. 2 is a longitudinal sectional view with the cross bars in elevation. Fig. 3 is a section on the line 3—3 of Fig. 1.

The same letters of reference designate the same parts or features as the case may be wherever they occur.

Referring to the drawings, the post is shown as comprising a body proper 5 and an anchoring base 6, the latter being formed with a screw-threaded surface 7. The base is further protected and strengthened by means of a metallic sheath 8 fitting thereover and correspondingly threaded internally and externally, the threads formed upon the post base engaging with the internal threads of the sheath, to retain the latter in place upon said base.

In practice, the sheath is first formed and is placed within the mold in which the post is cast, the cement or other material forming the post hardening within the sheath and conforming to the threads thereof, so that the base of the post and the sheath are to all intents practically integral. The post may, however, if desired, be cast independently of the sheath, which latter is then fitted over the post base and held in place thereon by the correspondingly threaded surfaces.

Extending through the longitudinal center of the entire post is a hollow rod 9, provided with a series of laterally disposed radiating arms 10, the said rod and arms forming a skeleton brace frame, as will be readily understood. The upper end of rod 9 projects slightly above the upper face of the post, and is provided with a hitching ring 11.

To permit the stringing of wires or their attachment thereto, the post body 5 is formed with a series of openings or passages 12, disposed one above the other and extending laterally therethrough from side to side, rod 9 being likewise provided with perforations 13 for that purpose. The post may also be provided with a further series of lateral openings, extending from the front face to the rear face of the post and through corresponding perforations in rod 9.

In practice, the post is cast in a suitable mold in the usual manner, the hollow rod

having first been placed therein, the post being formed with or without the sheath, as above described.

The tapered formation of the base and sheath, and the provision of threads thereon, prevent any portions of the base which may have been cracked or broken off during shipment from falling out and leaving a space into which the sheath may be pressed inwards against the chipped or cracked surface.

What is claimed is:—

A concrete fence post having a threaded

tapered base formed continuously therewith and adapted to be embedded in the ground, 15 and a metallic sheath incasing said base and provided with internal and external threads, the threads upon the base of the post engaging with the internal threads of the sheath, to retain the latter in place upon said base. 20

In testimony whereof, I affix my signature, in presence of two witnesses.

WILLIAM H. KESSLER.
